PENCIL

William B. Lynch, Pasadena, and Elmer E. Frey,
Los Angeles, Calif.

Application June 18, 1934, Serial No. 731,170

5 Claims. (Cl. 120—18)

This invention relates to lead pencils, and particularly to those of the magazine type.

An object of the invention resides in the employment of more simple and positively acting means for feeding the leads from the magazine than heretofore provided and for establishing with more positive assurance true alinement of the lead with the conductor tube between the magazine and the tip end of the pencil.

10 A further important object is to provide a novel magazine assembly consisting of a very minimum of co-operable parts which can be readily inserted into the shell or removed therefrom and whose form and construction are otherwise such that 15 the work of assembling the pencil will be greatly simplified.

A still further object is to provide a magazine of large lead capacity and in which, through the provision of a novel form of feeder or lead pusher, 20 will enable the leads to be successively discharged into a conduit or conductor tube, in which latter a plurality of ordinarily equal length leads can be disposed in endwise relationship to each other so that by the intended functional action of the 25 aforementioned pusher or feeder, all of the leads in said conduit will be moved to effect the required feed of one thereof from the tip of the pencil and wherein the said pusher or feeder operates in conjunction with the clutch of the tip to prevent 30 the leads from slipping axially of the conduit.

A further object is directed to the novel form and construction of the parts and the co-ordinated relationship of one to the other, whereby to 35 secure the magazine assembly operatively applied within the shell of the pencil.

Another feature of patentable novelty is directed 40 to the form and design of a magazine which will hold a reasonably large number of leads and whose overall length is such that it will occupy approximately one-third the length of a shell of average length, say one which measures about five and a half or six inches and whose external diameter is between a quarter and a half inch.

45 Other objects and advantages will appear and be more fully understood as the description proceeds.

In the accompanying drawing,

50 Figure 1 is a vertical section through the pencil with parts in full lines;

Figure 2 is a vertical section on an enlarged scale through a portion of the pencil;

55 Figure 3 is a view in side elevation of a portion of the pencil;

Figure 4 is a transverse section on line 4—4 of Figure 2;

Figure 5 is a section on line 5—5 of Figure 2;

Figure 6 is a section on line 6—6 of Figure 2.

In carrying the invention into practice, use is 5 made of a hollow shell or casing 10 of suitable length and diameter, the same having a conventional clutch tip 11 formed with an axial bore 12 from which latter a lead can be fed as use thereof is desired.

10 Within the upper section of the shell is fitted a magazine and lead pusher assembly of the construction clearly illustrated in Figure 2 of the drawing. It includes a plug-like body 13 having an annular flat ledge 13a on which latter the 15 lower ends of the leads are adapted to freely rest so that a series of leads can readily move around the course defined by said ledge. Secured in the shell is a lead-conducting tube 14 of a form and of such internal diameter to enable leads to pass 20 therethrough without any material resistance being offered thereto. Its upper end passes into a bore 15 in the body 13 so as to hold the latter against rotary movement and its lower end opens to the bore 12 of the aforementioned tip 11 as 25 shown in Figure 1, whereby one lead after another can be fed from the said tip as required.

The magazine and lead pusher assembly further embodies a rotary shell-like lead holder 16, the same having an annular series of grooves 17 30 for the accommodation of a like number of leads, so that the lower ends of said leads can rest on the ledge 13a. The overall length of the entire magazine and pusher assembly is approximately equal to one-third the length of the shell 10, and 35 as illustrated, the lower end of the holder 16 has free rotary contact with said ledge. The upper end of the holder is offset laterally at 18 at the upper edge of the shell 10 and same is provided with an annular enlargement 19 which is milled 40 at 20 to enable same to be securely grasped between the fingers and the holder rotated.

A tube 21 passes through the lead holder 16 and same is concentrically related to said holder so that an intervening annular lead race is formed 45 between the two. Its lower end is fixedly mounted in the body 13 and its opposite end 21a comes flush with the upper edge walls of the enlargement 19. Mounted to rotate in the body 13 axially of the tube 21 is a feed screw 22, the 50 upper end of which is fitted with an eraser sleeve 23, whereby the screw can be manually rotated. The screw is formed with a coarse spiral groove 24 in which the lug 25 of a feed nut or pusher 26 is adapted to travel as the screw is turned. Said 55

nut or pusher is provided with a radial pusher lug 27 which is adapted to travel in the longitudinal guide slot 28 in the tube 21. Here, it will be observed that the upper end of the tube 21 is disposed in the enlargement 19 so that in one possible position of the nut, the lug 27 thereof will be above the adjacent groove 17 in said holder, thus enabling the lug to be fed against the adjacent end of the particular lead to be ejected from the magazine and fed through the conduit 14. A closure sleeve 29 is fixed to and extends about the upper end of the tube 21 and has a flange 30 which extends over the adjacent ends of the grooves 17 as shown in Figure 2, excepting, of course, a single one of said grooves, namely, the one from which the particular lead is being fed. It follows that when the nut 26 is in the position shown in Figure 2, the holder 16 can be turned to establish registration or alinement of a groove 17 with the bore 31 in the body 13 and the upper end of the conduit 14, preparatory to feeding the lead through said conduit.

Carried by the sleeve 29 is a spring dog 32 whose outer end is adapted to engage with the ratchet teeth 33 formed on the inner walls of the enlargement 19 of the lead holder. As the sleeve 29 is stationary on the tube 21, it follows that on turning the holder, the dog will yielding-ly engage the said teeth so as to co-act with each thereof and thus constitute, in part, a means for determining the number of leads in the holder at any time. The teeth 33 are positioned so that there is one thereof for each of the grooves 17, as shown in Figure 4, and they are also correlated to the annular indicating markings 34 exteriorly formed on the said shell 10. A pointer 35 on the portion 19 of the holder co-acts with the markings 34 and with the indicating letters E and F on the shell, so that one may readily determine at a glance the exact number of leads in the magazine.

From the foregoing, it follows that means are provided for delivering a single lead from the magazine and for feeding same through the conduit 14. The conduit 14 always remains full, regardless of whether the magazine is full or empty. The pusher lug 27 serves as a constant abutment for the lead column so that the leads in said column cannot be pushed back or upwardly in the conduit. This, in combination with any well known form of friction means at the tip 12, insures a perfect feeding of the leads at all times. When it is desired to supply the magazine with leads, the cap 36 is removed from the eraser sleeve 23 and the holder is successively rotated to enable one lead at a time to be placed in the holder and the lower ends of the leads brought into resting engagement with the supporting ledge 13a.

The mechanism is exceedingly simple and a positive end-to-end engagement of the leads can be effected from a point starting at the lead holder to a point ending some place in the conduit 14. By means of the described relationship of the parts and the construction thereof, the magazine and lead pusher assembly can be compactly positioned in a pencil shell or casing of average length and the capacity for the leads will be quite large.

70 What is claimed is:

1. A lead magazine and lead pusher assembly for pencils comprising means having a ledge on which the adjacent ends of an annular series of leads are adapted to freely rest, the said ledge having a lead discharge passage, a rotary lead

holder mounted on the ledge to effect registration of a lead with the discharge passage, and means to feed the lead through said passage, and comprising a screw having one end journaled to rotate in the ledge; and a lead pusher mounted on the screw to move longitudinally thereof as the screw is turned and having a portion adapted to engage a lead to force same through said passage and means for holding the lead pusher against rotation. 10

2. A lead magazine and lead pusher assembly for lead pencils comprising a body having an annular ledge on which the adjacent ends of leads can rest so as to move annularly on the ledge, the body having a passage through which a single one of the leads can pass, a pair of concentrically positioned spaced tubes between which the leads can be placed in an annular series, the outer one of the tubes having longitudinal spaced-apart grooves in each of which a lead 20 can be accommodated with its lower end resting upon the ledge as aforementioned, and the said outer tube being mounted for rotation, means for turning the outer tube to establish successive registration of the grooves with said passage, 25 and slidably mounted lead pushing means contained in the inner tube and having a lug engageable against the opposite end of each lead as the leads are successively registered with the passage and adapted, during sliding movement 30 in one direction of the pushing means, to push the lead through said passage.

3. A lead magazine and lead pusher assembly for lead pencils comprising a body having an annular ledge on which the adjacent ends of leads can rest so as to move annularly on the ledge, the body having a passage through which a single one of the leads can pass, a pair of concentrically positioned spaced tubes between which the leads can be placed in an annular series, the outer one of the tubes having longitudinal spaced-apart grooves in each of which a lead can be accommodated with its lower end resting upon the ledge as aforementioned, and the said outer tube being mounted for rotation, means for turning the outer tube to establish successive registration of the grooves with said passage, slidably mounted lead-pushing means contained in the inner tube and having a lug engageable against the opposite end of each lead as the leads are 50 successively registered with the passage and adapted, during sliding movement in one direction of the pushing means, to push the lead through said passage, means carried by the inner tube, means carried by the outer tube, the latter co-operable with the former to determine operative registration of a lead with said passage. 55

4. A lead magazine and lead pusher assembly for lead pencils comprising a body having an annular ledge on which the adjacent ends of leads can rest so as to move annularly on the ledge, the body having a passage through which a single one of the leads can pass, a pair of concentrically positioned spaced tubes between 60 which the leads can be placed in an annular series, the outer one of the tubes having longitudinal spaced-apart grooves in each of which a lead can be accommodated with its lower end resting upon the ledge as aforementioned, and the said outer tube being mounted for rotation, means for turning the outer tube to establish successive registration of the grooves with said passage, slidably mounted lead-pushing means contained in the inner tube and having a lug engageable against 70

the opposite end of each lead as the leads are successively registered with the passage and adapted, during sliding movement in one direction of the pushing means, to push the lead 5 through the said passage, means carried by the inner tube, means carried by the outer tube, the latter co-operative with the former to determine operative registration of a lead with said passage, the said outer tube having a pointer thereon 10 exteriorly thereof, and a shell in which the magazine is mounted, the said shell having markings thereon with which the pointer is adapted to coincide.

5. A lead pencil comprising a shell having a lead feeding conduit contained therein, one end of which opens directly to the lead bore of the tip of the shell, the opposite end of the conduit being positioned a considerable distance inwardly of the opposite end of the shell, and a lead 15 magazine contained in that portion of the shell

between said opposite end of the shell and the second mentioned end of the conduit, and including means for alining a lead with the conduit, means for pushing the lead from the magazine and for feeding same through the conduit, 5 the magazine including a fixed ledge upon which the lower ends of leads can freely rest so as to move thereover, an inner stationary tube having a laterally opening longitudinal slot, an outer rotary tube between which and the inner tube 10 the leads can be placed in an annular series, the rotary tube functioning, when rotated a limited distance, to register a lead with the conduit, as aforesaid, and means contained in the inner tube and including a lug extending through said 15 lateral slot and into the space between both tubes for engaging against a lead to push same as aforementioned.
